UNITED STATES PATENT OFFICE.

GODFREY J. KAPLAN, OF OWATONNA, MINNESOTA, ASSIGNOR OF ONE-HALF TO LUTHERIA DISBROW AND ONE-HALF TO REUBEN B. DISBROW, OF OWATONNA, MINNESOTA.

COMBINED CHURN AND BUTTER-WORKER.

No. 840,133.

Specification of Letters Patent.

Patented Jan. 1, 1907.

Application filed April 25, 1906. Serial No. 313,651.

To all whom it may concern:

Be it known that I, GODFREY J. KAPLAN, a citizen of the United States, residing at Owatonna, in the county of Steele and State 5 of Minnesota, have invented certain new and useful Improvements in a Combined Churn and Butter-Worker; and I do hereby declare the following to be a full, clear, and exact description of the invention, such as will enable 10 others skilled in the art to which it appertains to make and use the same.

My invention has for its object to provide an improved machine adapted for use as a butter-worker or as a combined churn and butter-worker; and to this end it consists of the 15 novel devices and combinations of devices hereinafter described, and defined in the claims.

In the accompanying drawings, which 20 illustrate the invention, like characters indicate like parts throughout the several views.

Referring to the drawings, Figure 1 is a view in side elevation, showing the improved machine. Fig. 2 shows the drum or body of the churn in end elevation, but with certain other parts sectioned on the line $x^2 x^2$ of Fig. 1, and Fig. 3 is a transverse vertical section taken on the line $x^3 x^3$ of Fig. 1. Fig. 4 is a view corresponding to Fig. 3, but illustrating 30 a slightly-modified form.

In this improved machine a horizontally-disposed drum 1 of any suitable construction, but preferably having peripheral doors 2, is employed. Heavy gudgeons 3 and 4 project 35 axially outward from the opposite heads of the drum, and these are journaled in suitable bearings of a pair of bearing-brackets 5 6, which brackets, as shown, are tied together by rods 7.

Within the drum is a plurality of deeply-corrugated rollers 8, that extend parallel to the axis of the drum and are spaced equidistant from the said drum-axis and are spaced equidistant apart. Secured to the 45 inner surface of the drum radially outward from each roller 8 is a lifting shelf or flight 9, that extends, preferably, from end to end of the drum. Each roller 8 co-operates with one of the shelves—to wit, the adjacent shelf 50 9; but some little space should be left between the most nearly approaching portions of the said co-operating rollers and shelves.

Means is provided for rotating the drum in

one direction and for rotating the rollers 8 in an opposite direction upon their own axes. 55 For instance, if the drum 1 is rotated in the direction of the arrow marked adjacent thereto on Fig. 3 the said rollers 8 should be rotated in the direction of the arrows marked adjacent thereto in the same view. Simple 60 and efficient means for imparting the above-noted movements to the said drum and rollers is illustrated in the drawings and, as shown, comprises as follows: A large internal ring-gear 10 is secured to one head of the drum— 65 to wit, to the right-hand head thereof—as shown in Fig. 1. The shafts or trunnions 8^a of the rollers 8 project through the same head of the drum and at their outer ends are provided with sprocket-wheels 11. Mounted in 70 suitable bearings on their brackets 6 and on a shelf 6^a thereof is a driving-shaft 12, which at its outer end carries a pulley 13 and at its inner end carries a spur-pinion 14, which latter meshes with the ring-gear 10. Said driving-shaft also carries a sprocket 15. The drum-trunnion 4 carries two sprockets 16 and 17, the former of which alines with the roller-sprockets 11 and the latter of which alines with the driving-shaft sprocket 15. A 75 sprocket-chain 18 runs over the sprockets 15 and 17. A sprocket-chain 19 runs over the roller-sprockets 11 and under the drum-sprocket 16.

The use of the machine as a butter-worker 85 will first be described.

Under the rotation of the drum in the direction of the arrow marked in Fig. 3 the co-operating rollers 8 and lifting-shelves 9 will be brought into action in succession on the 90 mass of butter, which normally lies or tends to lie at the bottom of the drum, and will lift the same or cause the same to rise with the upwardly-moving part of the drum. While the butter is being lifted the roller 8, 95 which is acting thereon, cuts off portions from the lower part of the mass of butter and forces the same below the co-operating lifting-shelf 8. Most of the mass of butter will thus be cut up and worked through between the co-operating roller and lifting-shelf before the butter is carried to a point high enough to cause it to roll inward over the top of the roller to the center of the drum; but any surplus of butter or butter which is not worked 100 through between the roller and shelf will of 105

- course be carried over to the center of the drum and again dropped to the bottom of the drum to be again commingled with the main body of the butter. By the above-described 5 action the butter is not only worked in the sense that it is compressed and the water worked therefrom, but is cut up and then again commingled in such manner that there is a constant change and thorough commingling of all parts of the body of the butter. This manner of working the butter makes it possible to accomplish a substantial perfection in the distribution of salt throughout the body of the butter.
- 15 Hitherto, so far as I am aware, rollers which have been used to work butter have been caused to rotate on their own axes in the same direction as that of the rotation of the drum. I believe it to be broadly new to 20 rotate the working rollers in a direction reverse to that of the rotation of the drum and to provide means for coöperation therewith, whether fixed or movable, whereby the butter is cut or disintegrated and thereafter re- 25 commingled. Hence I desire to claim this feature broadly.
- The machine above described may be treated simply as a butter-worker or as a combined churn and butter-worker. In the 30 butter-working action the machine may be run at quite a high rate of speed, partly because of the simplicity of construction, but more particularly because of the coöperating action of the rollers and lifting-shelves.
- 35 Hence the machine may without change in its speed or readjustment of its parts be used either as a churn or butter-worker. In lieu of the lifting-shelves 9 rollers 9^a may be employed, as shown in Fig. 4. These rollers 9^a 40 if loose will in the butter-working action be frictionally driven in a direction reverse to that of the rotation of the coöperating rollers 8. If positively driven, said rollers 9^a should be driven in a direction reverse to that of the

rotation of the coöperating rollers 8. In any 45 event the rollers 8 and 9^a would serve to cut portions from the bottom of a mass of butter being lifted thereby.

I claim as my invention—

1. In a machine of the kind described, the 50 combination with a rotary drum and a plurality of rollers therein eccentric to the axes thereof, said drum having internal means co-operating with said rollers to lift the butter and to cut portions from the bottom thereof, 55 and driving means for rotating said drum in one direction and for rotating said rollers on their own axes in an opposite direction to that of the rotation of the drum, substantially as described.

2. In a machine of the kind described, the combination with a horizontally-disposed rotary drum and a plurality of corrugated rollers mounted therein eccentric to the axes thereof, said drum having internal lifting-shelves outward of and coöoperating with the several rollers, and driving connections for rotating the drum in one direction and for rotating said rollers on their own axes in an opposite direction to that of the rotation of 70 the drum, substantially as described.

3. In a machine of the kind described, the combination with a horizontally-disposed rotary drum provided with three internal lifting-shelves 9, and three internal eccentric 75 working rollers 8 each coöperating with one of said lifting-shelves, and driving connections for rotating said drum in one direction and for rotating said rollers on their own axes in a direction opposite to that of the rotation of the drum, substantially as described.

In testimony whereof I affix my signature in presence of two witnesses.

GODFREY J. KAPLAN.
